(57) **CLAIM**

The ornamental design for a transparent wardrobe locker door with single point recessed handle, as shown and described.

DESCRIPTION

FIG. 1 is a front top perspective view of a transparent wardrobe locker door showing our new design;

FIG. 2 is a bottom plan view thereof, the top plan view being identical to the bottom plan view;

FIG. 3 is a rear elevational view thereof;

FIG. 4 is a left end elevational view thereof, the right end elevational view being identical to the left end elevational view; and,

FIG. 5 is a top front perspective view of a transparent wardrobe locker door showing a further embodiment of our new design.
